US00D753695S

(12) United States Design Patent
Dye et al.

(10) Patent No.: US D753,695 S
(b4) Date of Patent: * Apr. 12, 2016

(54) DISPLAY SCREEN OR PORTION THEREOF
WITH GRAPHICAL USER INTERFACE

(71) Applicant: Apple Inc., Cupertino, CA (US)

(72) Inventors: Alan C. Dye, San Francisco, CA (US);
Aurelio Guzmán, San Jose, CA (US);
Jonathan P. Ive, San Francisco, CA (US); Christopher Wilson, San Francisco, CA (US)

(73) Assignee: Apple Inc., Cupertino, CA (US)

() Term: 14 Years

(21) Appl. No.: 29/501,083

(22) Filed: Sep. 1, 2014

(51) LOC (10) Cl. 14-04

(52) U.S. Cl.

USPC D14/486

(57) CLAIM

The ornamental design for a display screen or portion thereof with graphical user interface, as show and described.

DESCRIPTION

FIG. 1 is a front view of a display screen or portion thereof with graphical user interface showing our new design; and, FIG. 2 is a front view of a display screen or portion thereof with graphical user interface showing our new design. The outermost broken lines in the figures show a display screen or portion thereof, and form no part of the claimed design. The other broken lines in the figures show portions of the graphical user interface that form no part of the claimed design.

1 Claim, 2 Drawing Sheets
